CLOCK

Edward F. Farrens, Stockton, Calif., assignor of forty per cent to Richard Foo, Stockton, Calif.

Application August 16, 1938, Serial No. 225,157

2 Claims. (Cl. 58—125)

This invention relates generally to clocks, and in particular is directed to improvements in that type of portable clock which includes dual dials facing in opposite directions and a single motor unit disposed therebetween; the motor being arranged by suitable mechanism to drive the hour and minute hands of each dial in the proper direction.

The principal object of the present invention is to provide, in a clock of the type described, a simplified drive mechanism for the hands of the opposed dials.

Another object of the invention is to provide a portable, opposed dial clock which may include a standard clock motor with only slight alterations; this feature being important as a manufacturer can produce both single and opposed dial clocks without the necessity of designing and manufacturing a special drive motor or clock-work mechanism.

As an opposed dial clock cannot have the winding and setting controls on the back as is usual, it is also an object of the invention to provide an assembly whereby the controls are accessible from a point between the dials of the clock; the usual winding and setting shafts of the standard motor being included in such assembly.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figure 1 is a front view of the clock illustrating the added dial, partly broken away.

Figure 2 is an end elevation of the clock; the case being shown in section.

Figure 3 is a cross section taken substantially on line 3—3 of Fig. 2.

Figure 4 is an enlarged, fragmentary plan view, somewhat diagrammatic, of the added direction changing gear mechanism.

Referring now more particularly to the characters of reference on the drawings, the numeral 1 designates a cylindrical clock case which is initially open at its ends; such case being supported by a hollow, open bottomed base 2. The ends of case 1 are fitted with glass faces, indicated at 3 and 3a, which are mounted in place in the usual manner.

The main clockwork mechanism or motor unit,

including the alarm wind spring motor 4, is of standard construction, and is confined between the usual front plate 5 and back plate 6 secured together by means of tie bolts 7. In the present device, the plate tie bolts 7 are extended, as at 7a, and support an additional plate 8 behind the plate 6 which actually becomes and will now be termed the back plate, while plate 6 will be described as the intermediate plate. The motor unit and including the additional plate are mounted within the case 1 by brackets 9 to which are secured the outer ends of the extended portions 7a of the tie bolts.

One dial 10 is supported intermediate plate 5 and glass face 3 by fingers 11 which are mounted on and project from said plate; while another dial 10a is similarly mounted between plate 8 and glass face 3a by means of fingers 11a. The dial 10 is the one included in a single dial clock, as is the minute hand 12 mounted on the drive shaft 13; the hour hand 14 being carried as usual on a sleeve 15 surrounding shaft 13 and driven at reduced speed by the usual train of gears 16 mounted on plate 5.

The minute hand 17 for dial 10a is mounted on a stub shaft 18 which extends inwardly through back plate 8; such stub shaft being aligned with but separate from the minute hand shaft 13 of the clock motor as shown in Fig. 4. The hour hand 19 for dial 10a is carried by a sleeve 20 which surrounds shaft 18, the sleeve being driven at reduced speed by a chain of gears 21 mounted on plate 8. The mounting of hands 17 and 19 in connection with shaft 18 and the operation of the hands therefrom is common practice and the same as heretofore described relative to hands 12 and 14 for dial 10.

However, it is necessary that shaft 18 be driven from the motor in a reverse direction relative to the direction of movement of shaft 13. I accomplish this result by means of the following mechanism which is simple in structure and inexpensive to manufacture:

A countershaft 22 is journaled between plates 6 and 8 to one side of but parallel with shafts 13 and 18. A gear 23 is fixed on shaft 13 adjacent the side of plate 6 away from plate 8, while another gear 24 of the same size is fixed on countershaft 22 adjacent the same side of plate 6. An intermediate gear 25 is journaled on plate 6 and meshes with said gears. Countershaft 22 is thus driven in the same direction as shaft 13.

A gear 26 is fixed on the countershaft adjacent plate 8 and meshes with a like sized gear 27 fixed on the inner end of shaft 18. With the two gear

trains above described, shaft 18 is rotated in the opposite direction to the direction of rotation of shaft 13 as is necessary to provide proper directional movement of hands 17 and 19 relative to 5 dial 10a. To assure the alinement of shafts 13 and 18, the hub 27a of gear 27 forms a bearing for the adjacent end of shaft 13 and in which hub said shaft turns.

In order to provide accessible setting and winding controls for the clock, the time winding shaft 28, the alarm winding shaft 29, and the alarm setting shaft 30 are each extended from plate 6 to plate 8 as shown. Separate control rods 31, 32 and 33 respectively are bracket supported either on plates 6 or 8 and extend downward from a point adjacent the several extended shafts to a termination in the hollow, open bottomed base 2 where they are provided with the usual finger members indicated at 34, 35 and 36. Pairs of 10 bevel gears 37, 38 and 39 respectively are mounted in connection between and transmit motion from the rods to the corresponding shafts. The control rod 40 for shaft 13 is mounted in the same manner as the other rods and includes a finger 15 member 41; a bevel gear unit 42 connecting the rod 40 and shaft 13. As shaft 13 rotates continuously to drive the hands for both dials, I reduce the frictional drag on such shaft by including a spring 43 on rod 40 which acts to normally shift rod 40 lengthwise and hold the bevel gear thereon out of mesh with the corresponding gear on shaft 13.

From the foregoing description it will be readily seen that I have produced such a device as 20 substantially fulfills the objects of the invention as set forth herein.

While this specification sets forth in detail the present and preferred construction of the device, still in practice such deviations from such detail may be resorted to as do not form a departure from the spirit of the invention, as defined by the 5 appended claims.

Having thus described my invention, what I claim as new and useful and desire to secure by Letters Patent is:

1. In combination with a clock movement having front and rear frame plates, and a minute-hand shaft projecting rearwardly of the rear plate, tie rods connecting the plates and projecting rearwardly of the rear plate, a third plate disposed rearwardly of said rear plate and 15 secured on the projecting portions of the tie rods, another minute-hand shaft turnably supported in said third plate and axially alined with the first named shaft, and a gear train connecting the shafts to cause said second named shaft to 20 turn in a direction opposite to that of the first named shaft and mounted partly on the rear plate and partly on said third plate.

2. In a dual face clock movement, separate 25 axially alined minute-hand shafts whose inner ends are adjacent each other, a reversing gear train between the shafts including a gear having a relatively long axial hub into one end of which the inner end of one shaft projects in non-turning engagement and into the other end of which the 30 inner end of the other shaft projects in turning relation.

EDWARD F. FARRENS. 35
